UNITED STATES PATENT OFFICE.

CHRISTOPHER J. CLIFFORD, OF LONG ISLAND CITY, NEW YORK.

DOOR-HANGER.

1,083,803.

Specification of Letters Patent.

Patented Jan. 6, 1914.

Application filed September 25, 1912. Serial No. 722,274.

To all whom it may concern:

Be it known that I, CHRISTOPHER J. CLIFFORD, a citizen of the United States, residing at Long Island City, in the county of Queens 5 and State of New York, have invented new and useful Improvements in Door-Hangers, of which the following is a specification.

This invention relates to door hangers and has for an object to provide a device of this 10 character which will include companion race-ways of a door structure and similar race-ways of a barn structure; arranging the race-ways of the door with such relation to those of the barn that anti-friction bodies 15 may be disposed therebetween, sustaining the weight of the door in such manner that it may be opened or closed with the minimum power, and then further, the provision of means for spacing the anti-friction bodies 20 relatively and for clearing the raceway of the anti-friction bodies at different positions of adjustment of the door.

Other objects will appear and be better understood from that embodiment of my invention of which the following is a specification, reference being had to the accompanying drawings forming part hereof, in which:

Figure 1 is a front view of the hanger 30 showing the application of the same to a sliding door. Fig. 2 is a rear view thereof detached from the door. Fig. 3 is an end view thereof. Fig. 4 is a section on the line 4-4 of Fig. 2. Fig. 5 is a section on the 35 line 5-5 of Fig. 1. Fig. 6 is a top plan view of the supporting member.

The hanger is shown to include a substantially L supporting bar 1 which may be secured to one wall of the building or structure A. Said bar is provided with a horizontally disposed flange 2 having a fixed upper rail 3 and a similar fixed lower rail 4, each having a continuous race-way 5 for a purpose to be hereinafter explained. A 45 rail 6 secured to the flange 7 of an L bar 8, is disposed above the rail 3 and provided with a raceway 9 which is associated with the raceway 5 of the rail 3 so that the latter and the former operatively accommodate the 50 spherical anti-friction bodies 10. A spacing plate 11 is interposed between the rails 3 and 6, and as shown, it has vertical passages 12 through which the bodies 10 are projected. Said plate serves to hold the bodies 55 against crowding against each other, while it also acts as a cleaner to remove foreign

particles from the path of the bodies as the door is moved in one direction, one end of said plate being extended in a downward direction as at 13, whereby to lie in effective 60 scraping contact with the walls of the race-way 5 in the rail 3.

Straps 14 are secured in any suitable manner to the rail 6, and as illustrated said hanger extends downward in front of the 65 flange 2 of the support 1, and they are provided with horizontal attaching portions 15, carrying bolts 16 to be secured to the door B. Said attaching portions 15 carry bosses 17 which are located beneath the raceway 5 70 of the rail 4, accommodating therewith the spherical anti-friction bodies 18. A guard 19 is secured to the front edge of the flange 2 and projected into the relatively long recess 20 and adapted to contact with the walls 75 21 and 22 thereof so as to prevent the plate 11 from accidentally escaping from the bodies 10 and to prevent the latter from becoming misplaced from the raceways.

What is claimed as new is:

1. In a door hanger of the character described, the combination of a supporting bar substantially L-shaped and disposed against a wall of a building, so as to provide a horizontally projecting flange, a channeled rail secured to the upper side of the flange adapted to serve as a raceway for anti-friction balls, a similar rail provided upon the lower side of said flange, an apertured plate adapted to rest upon the upper 85 rail, a plurality of anti-friction balls disposed through said apertures and resting in the channel of said rail, a channeled bar disposed in an inverted position above said plate and resting upon said balls, 90 a flanged bar secured to said bar, supporting straps for the door suitably secured to the flanged bar, said straps having a horizontally disposed connecting bar and bosses adapted to support anti-friction balls 95 adapted to move in the inverted rail upon the lower side of the flange of the supporting rail, substantially as and for the purposes set forth.

2. In a door hanger of the character described, the combination with a supporting rail, a channeled rail provided upon the upper side of said rail, said channel serving as a raceway for anti-friction bodies, a second channeled rail shorter than the first 100 said rail disposed in an inverted position above the first rail and engaging the anti-

friction bodies and resting thereon, a supporting bar having a depending flange secured upon said second rail, and hanger straps adapted for supporting a door secured 5 to the said bar; of a perforated plate of suitable length disposed between the said channeled rails, said plate having apertures suitable for admitting said anti-friction bodies whereby they may be retained in 10 proper relative position in said channeled rails, means for securing said plate between

15 said rails, said plate having its end deflected and disposed within the channel of the first rail and serving to clear the race-way of obstructions.

In testimony whereof I affix my signature in presence of two witnesses.

CHRISTOPHER J. CLIFFORD.

Witnesses:

JOHN A. DONEGAN,
C. JAMES CRONIN.
